Primary Examiner — Omeed Agilee(74) *Attorney, Agent, or Firm* — Burr & Forman LLP(57) **CLAIM**

The ornamental design for a hedge trimmer, as shown and described.

DESCRIPTION

FIG. 1 is a perspective view of an hedge trimmer of the present invention;

FIG. 2 is a front view of the hedge trimmer of FIG. 1;

FIG. 3 is a rear view of the hedge trimmer of FIG. 1;

FIG. 4 is a left side view of the hedge trimmer of FIG. 1;

FIG. 5 is a right side view of the hedge trimmer of FIG. 1;

FIG. 6 is a top view of the hedge trimmer of FIG. 1; and,

FIG. 7 is a bottom view of the hedge trimmer of FIG. 1.

The broken lines in the drawings depict portions of the hedge trimmer that form no part of the claimed design.
